YARN GUIDING DEVICE

Arthur L. Jackson, West Asheville, N. C., assignor
to American Enka Corporation, Enka, N. C., a
corporation of Delaware

Application February 13, 1941, Serial No. 378,811

6 Claims. (Cl. 242—18)

This invention relates to the winding of yarns, threads and the like, and is more particularly concerned with thread guides employed in such operations.

In the winding of thread or the like, regardless of the technique employed or the machinery used, it has long been customary to provide guides to insure the maintenance of the moving thread in a predetermined path of travel, adequate control being otherwise impossible of attainment. 10 Generally speaking, this control is of two types; one in which thread must be maintained in a single path of travel, and the other in which thread must be directed by the guide into various paths of travel. In the first instance, the 15 relative positions of the guide and thread path are constant while in the second there is relative movement between the thread guide and any single thread path. Since winding speed is a prime consideration in operating efficiency, it is 20 readily recognized that speed in threading up is secondary in importance only to the proper functioning of the guide in maintaining the thread in its proper path.

The problem of maintaining thread in a path of travel can, of course, be solved by the provision of any type of encircling eyelet, this construction, however, requiring a slow and tedious threading up operation consisting in passing the end of the thread through the eye. To overcome these slow threading difficulties, the well-known "pigtail" guide was developed and has met with wide success when used in operations where the thread guide maintains a fixed position.

On the other hand, the type of guide which moves, such as that used as a part of a traverse mechanism, cannot be constructed in the manner of a "pigtail" guide since the surface of the guide must be rounded to contact a thread package and the guide must maintain a confining action even while exerting force in a lateral sense to cause thread displacement. Thus, the conventional thread guide which moves with respect to a single path of thread travel is, as at present constructed, merely a segment of a sphere having a radial groove therein adapted to receive the thread. The rounded surface of this type of guide, which is commonly designated in the winding industry as a button, is adapted to contact a thread package while the tension of the thread serves to maintain the same within the confines of the groove. Such a guide, not being an encircling one, presents no threading up difficulties but is the cause of frequent and

costly delays in winding operations arising from the thread riding out of the groove.

While the above problem arises as an incident in all types of winding operations involving a moving thread guide, a particular problem has arisen in the coning of rayon threads into package form suitable for shipment to the consumer.

The coning operation consists essentially in the winding of already treated and twisted thread onto a conical support to produce a dense, firm package suitable for economical and efficient transportation. Usually a driven cone draws thread upwardly from a source of supply and a traverse mechanism lays up the thread on the cone in successive oppositely directed helical courses. The traverse mechanism may consist of a bar caused to reciprocate and an arm carried by said bar and overlying the cone. A thread guide or button is mounted on the free end of this arm to direct the thread onto the cone. Inasmuch as a dense hard package is desired, considerable tension is applied to the thread and the traverse arm is counterweighted to maintain the button in firm engagement with the cone or package. Because of the considerable tension to which the thread is subjected the traverse button of conventional construction can be used with reasonable assurance that the thread will be retained in the groove thereof. However, also as an incident of thread tension, breakage is a fairly frequent occurrence. This results in stoppage of a unit of the coning machine and requires the attention of the operator to tie the ends and possibly to thread up again. During the stoppage of the machine, while knotting of the several thread ends is accomplished, considerable slack is formed which, of course, must be removed before normal operation may be resumed. Generally slack is removed by manually pulling a loop between the traversing thread guide and the cone, the latter being started slowly and allowed to take up the loop gradually. This operation, when performed in conjunction with conventional machinery, frequently results in the thread jumping out of the traverse button to become ensnared in the machine thereby again causing stoppage and further costly delay in production. Furthermore, regardless of the problem of removal of slack, smooth, lubricated threads of synthetic origin even under considerable tension may rather readily become displaced from a conventional type traverse button which is non-encircling in character.

It is, therefore, an object of this invention to

overcome all of the foregoing disadvantages and to provide a thread guide which entirely surrounds and confines a moving thread, is self-threading and may be relatively moved with respect to a thread path with full assurance that the thread will not become disengaged.

According to this invention it is contemplated that traverse guides may be designed to entirely encircle and confine a moving thread while fully retaining the self-threading and package contacting advantages of conventional traverse buttons.

It is a further object of this invention to provide a simple, inexpensive and easily constructed thread guide of wide general utility, characterized by freedom from protruding edges where thread is likely to become snarled.

Other objects and advantages of this invention will be apparent upon a consideration of the following detailed description of a preferred embodiment thereof in conjunction with the annexed drawing wherein:

Figure 1 is a view in end elevation of a portion of a conventional cone winding mechanism showing one form of the novel thread guide operatively associated therewith;

Figure 2 is a view in rear elevation of the thread guide per se showing the thread contacting face of the traverse button;

Figure 3 is a view thereof in side elevation;

Figure 4 is a view thereof in front elevation; and

Figure 5 is a top plan view illustrating the spacing between the button and its supporting structure whereby the guide is rendered self-threading.

The portions of a conventional winding machine that are shown in Figure 1 consist of a cone winder 10 such as a cardboard cone or other core for a thread package 11. A weighted lever 12 is pivoted below the cone center and is provided with a groove 13 in its upper end receiving traverse bar 14 which is caused to reciprocate by a cam arrangement of conventional construction (not shown).

A preferred form of thread guide, constructed according to the present invention, is shown attached to traverse bar 14 and extending into thread distributing position.

This thread guide consists of a shank or stem portion 15 in the form of a flat plate having a foot 16 attached to the traverse bar 14. At the end of shank or plate 15 remote from foot 16, it is provided with an integral head portion 17 having therein a reentrant recess at 18 opening at 19 generally at a right angle to the long axis of the shank. Recess 18 extends from the opening toward the free end of the shank 15. Underlying head portion 17 of shank 15 is a thread button 20 having therein a V-groove at 21 which opens in the direction of the cone winder 10 and consequently away from the foot 16. Thread button 20 is in the form of a segment of a sphere, the convex surface being disposed in thread package contacting position.

Upon reference to Figures 2 and 4, it will be seen that the bottom of V-groove 21 of button 20 is disposed in registry with the bottom of reentrant recess 18, the head 17 of shank 15 and the button 20 together defining an encircling thread aperture. Screws 22 serve to connect thread button 20 and the head 17 of shank 15. It is an important phase of this invention that the point of attachment of these two members be on the same side of shank 15 as the mouth 19

of reentrant recess 18, and that the point of attachment lie between said mouth and the mouth of V-groove 21. The reason for this is clear upon consideration of Figure 5, wherein it will be seen that head 17 of shank 15 is sprung outwardly at 23 on the side of button 20 opposite the side receiving screws 22 for the purpose of spacing said head and said button. Thus, at the side of the guide having no laterally extending recess, button 20 and its support, head 17, are spaced while on the side having mouth 19 of reentrant recess 18 therein screws 22 serve to block the passage of thread between button 20 and head 17.

When the machine shown in Figure 1 is used in a winding operation, a thread 24 is passed from a source not shown through the various guides of the machine and finally across bail 25, through the guide just described for attachment to cone winder 10. Cone winder 10 is then caused to be driven and thread 24 is wound thereon in a series of oppositely directed helical courses under the control of traverse bar 14 acting through the novel thread guide.

Because of the fact that button 20 and head 17 are attached at a point within the sector defined by the mouth of groove 21, mouth 19 and the thread aperture, thread 24 will be fully confined by the guide even while it is exerting lateral force to cause the thread to be laid up under control of traverse bar 14. The reason for the confinement will be evident when it is borne in mind that at the side of head 17 having mouth 19 therein, screws 22 function to prevent thread from passing out of groove 21 between button 20 and head 17 to escape through mouth 19 while on the opposite side of recess 18 head 17 presents an unbroken surface even though button 20 and head 17 are there spaced apart. Of course, the top edge of head 17 fully closes the mouth of groove 21 as can be readily seen in Figures 2 and 4.

Despite the fact that the thread guide defined by button 20 and head 17 is of the encircling type it is entirely self-threading it being necessary only to manually introduce a length of thread into mouth 19 with the portion thereof between bail 25 and the guide above shank 15 as shown in Figure 4 and the portion between groove 19 and cone winder 10 beneath head 17 and button 20 as viewed in the same figure. Thereafter a loop may be pulled to the right of Figure 4 and the thread allowed to pass between button 20 and head 17 at 23 to become seated in groove 21.

Although the thread guide shown is applied to a coning machine it will be recognized that it is readily adaptable to any type of winding apparatus the rounding of button 20 and the curvature of head 17 serving to eliminate edges of a type which have heretofore caused much snarling and attendant difficulty. While the guide is primarily designed for movement with respect to a thread path it may be employed without modification in a stationary position.

Having now described the invention in its preferred form, it is understood that variations and modifications may be made therein without departing from the spirit of the invention, and it is desired that the scope thereof be limited only by the appended claims.

What is claimed is:

1. A traversing thread guide comprising two members each having a recess therein opening marginally thereof, said members being superimposed with the openings of said recesses out of

registry but with the bottoms of said recesses in registry to define an encircling thread opening, said members being mutually attached only at a point within the right angle made by the mouth of one recess with respect to the mouth of the other, and a stem attached to one of the members.

2. A guide adapted to confine thread yarn or the like during a winding operation involving relative movement between the guide and the path of travel of the thread comprising, a member having a groove therein, a second member, a part of which overlies the first, said second member having a reentrant recess therein, a portion of which is in registry with a portion of the groove to define a thread encircling opening, the mouth of said recess being disposed at approximately a right angle with respect to the mouth of said groove, said members being attached only at a point within said right angle and being elsewhere spaced to form a thread entrance whereby the guide may be automatically threaded.

3. In a cone winding machine including a driven cone winder and a reciprocating traverse bar, an encircling thread guide for directing thread as it is laid up on said cone winder comprising, a cone contacting traverse button having a groove therein and means connecting said button to said traverse bar, said means having a reentrant recess therein opening laterally thereof and extending longitudinally away from said traverse bar, said button and said means being superimposed with the mouth of said groove opening in the direction of the cone winder and a portion of said groove and a portion of said recess in registry to define an encircling thread aperture, said means being attached to said button only on the side thereof having the mouth of the recess therein, said button and said means being spaced at the other side of the reentrant recess to form a thread entrance whereby the guide may be automatically threaded.

4. In a cone winding machine including a driven cone winder and a reciprocating traverse bar, an encircling thread guide for directing thread as it is laid up on said cone winder comprising, a cone contacting traverse button having a V-groove therein and an elongated rigid plate connecting said button to said traverse bar, said plate having a reentrant recess therein opening

laterally thereof and extending longitudinally in the direction of said cone winder, said button and a portion of said plate being superimposed with the mouth of said groove opening in the direction of the cone winder and with the bottom of the groove in registry with the bottom of the reentrant recess to define a thread encircling aperture, said plate and said button being attached only at a point between the mouth of said groove and the mouth of said recess on the side of said plate having the mouth of the recess therein, the button and plate being elsewhere spaced to form a thread entrance whereby the guide may be automatically threaded.

5. A thread guide for use in coning machines and the like comprising, a supporting stem, an integral plate carried thereby, said plate having a reentrant recess therein extending longitudinally away from said stem and opening generally transversely of the long axis thereof, and a member having a groove therein said member being superimposed on said plate with the mouth of the groove extending away from said stem but with a portion of the groove in registry with a portion of said recess to define a thread opening, said plate and member being attached only on the side of said plate having the mouth of the reentrant recess therein, the plate being bent to space the other side of the same from said member to form a thread entrance whereby the guide may be automatically threaded.

6. A thread guide for use in coning machines and the like comprising, a supporting stem, an integral plate carried thereby, said plate having a reentrant recess therein extending longitudinally away from said stem and opening generally transversely of the long axis thereof, a member having a groove therein said member being superimposed on said plate with the mouth of the groove extending away from said stem but with a portion of the groove in registry with a portion of said recess to define a thread opening, and means connecting said plate and said member only on the side of said plate having the mouth of the reentrant recess therein, the plate being bent to space the other side of the same from said member to form a thread entrance whereby the guide may be automatically threaded.

ARTHUR L. JACKSON.
